Inventor

Horace C. Whitten

UNITED STATES PATENT OFFICE.

HORACE C. WHITTEN, OF PLYMOUTH, MASSACHUSETTS, ASSIGNOR TO HIMSELF AND JOSEPH L. BROWN, OF SAME PLACE.

PORTABLE WRITING APPARATUS.

Specification forming part of Letters Patent No. 37,326, dated January 6, 1863.

To all whom it may concern:

Be it known that I, HORACE C. WHITTEN, of Plymouth, in the county of Plymouth and State of Massachusetts, have invented a new and useful Improvement in portable writing apparatus for the use of soldiers and others; and I do hereby declare the same to be fully described in the following specification, and represented in the accompanying drawings, of which—

Figure 1 denotes a top view of the said apparatus (or case and tablet) with the cover turned backward. Fig. 2 is a top view of the same, with the tablet unfolded or in position to serve as a support to a sheet of paper while being written upon. Fig. 3 is a transverse section of the case and the tablet, the latter being in an unfolded state, as shown in Fig. 2.

The nature of my invention consists in an improved writing apparatus, having its tablet and case combined and arranged in a peculiar manner with respect to each other, whereby the main portion and the cover not only serve to support the tablet when in use in a horizontal or the same plane, but the whole, when the tablet is folded and placed within its case, is rendered very compact for transportation.

In the drawings, A^2 represents a metallic case, which I usually make of a cylindrical form and in two parts, A B, of which A is the main part or body of the case, while B is the cover thereof, which is hinged to the main part, as seen in Fig. 1. The two heads $a a$ of the case A, I make of a circular form, and construct both the body portion and the cover semicircular in transverse section, in order that when the cover is turned backward to its greatest extent the two horizontal edges $b b$ of the cover and one of the edges c of the main portion shall serve as supports to maintain the tablet (when in an unfolded state and ready for use) in, or nearly in, the same plane, as shown in Fig. 2. The said part A has a plate, d , extending horizontally from one of its ends, and is soldered or otherwise secured to such end and to the edges $c c$, as shown in the drawings, the said plate having a cylindrical or other proper-shaped hole made

vertically through it for the reception of an inkstand, B, which is made to fit such hole and be firmly maintained in position therein. The inkstand employed may be such as is commonly used by soldiers, or any other that is of the proper size and has a liquid-tight cap or stopper.

D represents the tablet, which consists of a series of thin strips or bars, $ee e$, &c., arranged flatwise upon one side of a piece of cloth, leather, or other suitable flexible material, such bars being so applied in order that when the tablet is unfolded for use their inner edges may rest against and support each other, but when such tablet is not in use they may be readily folded into a small compass and packed within the case. The said tablet is attached to the inner side of the body portion A, and along and near one of its edges, c , by means of rivets, cement, or in any other suitable manner. The object of so attaching the tablet to its case is to allow the former to be well supported upon the edges of the cover and one of those of the case, when the tablet is brought into position for use. Furthermore, on the inner face of the tablet, and near the outer edge thereof, I arrange an elastic band, E, which serves to confine the sheet or sheets of paper in proper position while being written upon, as well as while being rolled up or packed for transportation or otherwise.

My improved apparatus is especially intended for soldiers, engineers, and travelers, it being so constructed as to be conveniently used in the open air as well as in the camp.

I lay no claim to the apparatus of H. C. Small, patented January 14, 1862, nor do I claim that of George C. Hathaway as patented December 24, 1861, my invention differing materially from either, for in my said invention I employ no portfolio, either in connection or combination with folding tablet or the same and its case; nor do I have any folding tablet, checker or chess board separate from the case, but I arrange and combine or apply a folding tablet and a case, or the main part and cover of such case, in a peculiar manner, whereby, when the tablet is unfolded or unrolled into a condition proper for supporting a sheet of paper while being written upon

such tablet may rest on the cover and be sustained both by the cover and the main part of the case; and, therefore,

I claim as my invention—

My improved portable writing apparatus, as made with its folding tablet D and the body or main part A and cover B of its case

A², arranged and applied substantially in manner and so as to operate as represented and described.

HORACE C. WHITTEN.
